UNITED STATES PATENT OFFICE.

LOUIS R. CUSTER, OF SOUTHMONT BOROUGH, PENNSYLVANIA.

INGOT MOLD.

1,409,084.

Specification of Letters Patent. Patented Mar. 7, 1922.

Application filed April 14, 1921. Serial No. 461,280.

To all whom it may concern:

Be it known that I, LOUIS R. CUSTER, a citizen of the United States, and a resident of the borough of Southmont, county of 5 Cambria, and State of Pennsylvania, have invented certain new and useful Improvements in Ingot Molds; and I do hereby declare the following to be a full, clear, and exact description of the invention, such as 10 will enable others skilled in the art to which it appertains to make and use the same.

My invention relates to ingot molds which are used for casting ingots therein from molten metal such as steel of various kinds 15 and qualities from the softest to the hardest qualities, either ordinary carbon steels or alloy steels of various compositions, including those made by different processes such as the Bessemer or open hearth processes 20 either acid or basic, crucible, electric furnace or otherwise and also may be used for casting ingots of any other metals to which such molds are applicable.

My invention relates particularly to ingot 25 molds the cross sections of which may be of any form, either square with rounded corners, rectangular, cylindrical, corrugated, or in fact any of the shapes into which ingots are cast, and my mold is of what is known 30 as the big-end-up type, that is the cross section of the mold cavity is larger at the top than at the bottom and preferably with a sink-head top in order to produce ingots which will cool properly in order to prevent 35 piping, which piping in ingots produced in other types of molds consists of internal cavities which are generally near the top of the ingot, but in many prior cases these pipes or cavities extend well down into the 40 ingot and thereby spoil a large portion of the same for the use intended by reason of such defects.

My mold in addition to being of the big-end-up type has its side walls made of considerable thickness and of greater thickness 45 than has been customary, and each side wall is of substantially uniform thickness from end to end or from the bottom or near the bottom to its top; these being distinctive 50 features of my invention. The substantially uniform thickness to which I refer relates particularly to the main or body portion of the mold although the lower portion may extend inwardly in order to produce a smaller 55 bottom end on the ingot, the lower portion of which will cool more rapidly against the

stool and the thicker metal of the mold by reason of the greater mass of the mold and stool so as to produce a better and more finished end and obviate fins or flanges of metal 60 which are apt to form at the bottoms of other molds and project between the molds and the stools on which they are set thereby causing shrinkage cracks in the ingot which will produce defects in the finished material, 65 and the fins will also prevent the easy stripping of the ingot or withdrawal of the same from the mold. These difficulties may be obviated to a certain extent by extending the bottom of the mold wall inwardly so that 70 the lower portion of my mold need not necessarily be of a thickness uniform with the major portion of the wall.

My molds may be made of cast iron, cast steel or other metals as desired.

In order to simplify the description I will herein confine it to molds for steel ingots, although as before stated my mold is adapted for use with any kind of metal. I also prefer to provide my ingot mold with 75 a refractory non-conducting sink-head top, which will retain the upper portion of the ingot fluid in order to feed the shrinkage cavity below as the ingot cools and thereby produce a solid ingot the only cavity being 80 in the sink head top which is discarded.

The walls of my mold are arranged with any usual or reasonable inside taper so as to allow the ingot to be readily withdrawn therefrom and in this big-end-up type the 85 cross section of the ingot is larger at the top than at the bottom as before stated. This form also is conducive to solid ingots for the reason that the shrinkage cavity or pipe is thereby concentrated in the sink 90 head top and the body of the ingot is substantially solid.

By reason of the comparatively great and substantially uniform thickness of my mold walls the cooling of the molten steel proceeds in the best manner and to a substantially uniform extent throughout the length of the ingot and mold, although on account of the fact that the mold walls are of substantially uniform thickness throughout 100 their length, the cooling effect of the mold on the ingot metal will be slightly greater at the bottom by reason of the fact that there is less steel near the bottom portion as compared with the conducting mass of the mold 105 but the mold mass is so proportioned and arranged relatively to the adjacent mass of

ingot metal throughout the mold length that while the ingot is cooled almost uniformly throughout its length it does cool to a slightly greater extent at the bottom, and 5 although the cooling of the ingot proceeds from the bottom upwardly it approaches very nearly a uniform cooling simultaneously throughout its length. This method of cooling is due to the great and substantially uniform thickness and proportion of 10 my ingot mold, which produces a much more regular internal physical structure throughout the ingot and a more uniform grain size throughout, on account of the substantially uniform heat-absorbing capacity 15 of the mold due to its substantially constant thickness and this produces an ingot which at the same time is solid and of more uniform chemical composition throughout. 20 On account of the character of the cooling due to my ingot mold the segregation of metalloids in the steel is also largely prevented, as they do not have time to separate as they do with ingot molds of the so-called 25 standard or prior forms. With thinner molds made as heretofore; thicker at the bottom than at the top the rate of cooling at the bottom is so much faster than elsewhere that the metalloids are segregated, 30 causing an ingot of varying composition in its different parts, all of which is largely obviated by my construction.

I have found by actual trial that as compared with prior practice my ingot molds 35 produce 15 per cent more by weight of good ingot material than those cast in the ordinary and prior manner.

In order to define within limits, the thickness of my mold walls, I may make the 40 thickness of these walls such that the mold itself will weigh from one and one-half to four times the weight of the contained ingot, but I prefer a mold that weighs from two to two and a half times the weight of the 45 contained ingot, as I have found that this produces the best results in the manner indicated and described above. The prior practice in this respect has been to make the ingot mold of a weight about equal to that 50 of the contained ingot and with walls thicker at the bottom than at the top so that my mold which is much heavier than the ingot and of substantially uniform thickness is a considerable departure from the prior practice and produces the good results desired as herein stated.

Having thus given a general description of my invention, I will now, in order to make the matter more clear, refer to the annexed sheet of drawings, which forms part 60 of this specification, and in which like characters refer to like parts.

Figure 1 is a vertical sectional elevation of one form of my ingot mold mounted on 65 a stool and provided with a sink head top,

this view being taken centrally and vertically through the sink head top, the ingot mold and the stool upon which it rests and the mold shown weighs approximately two and one-quarter times the weight of the ingot contained therein. Figure 2 is a vertical sectional elevation of a slightly modified form of my ingot mold taken centrally through the sink-head top, the mold and the stool, the mold having a slightly greater 70 inner taper near the bottom portion to make the bottom end of the ingot somewhat smaller, and the stool is shown with a projection extending inwardly into the mold and provided with sealing material such as 75 clay or slurry between the bottom of the mold wall and the projection in order to prevent a fin from being formed at the bottom of the ingot. This mold weighs about one and one-half times as much as the ingot 80 contained therein. Figure 3 is a vertical sectional elevation taken centrally through my ingot mold, sink-head top and stool, showing a slightly modified form of my mold, having a curved taper in the inner 85 bottom wall to produce an ingot with a smaller curved end, and the stool in this case has a plane top. Figure 4 is a top plan view of the sink-head top and ingot mold 90 illustrated in Figure 1, and Figure 5 is a top plan view of the stool shown in Figure 2. 95

Referring now to the characters of reference on the drawing:—1 is my ingot mold in general as illustrated in Figure 1, 2 is my ingot mold in general as illustrated in Figure 2, and 3 is my ingot mold in general as illustrated in Figure 3. 4 are the top lifting lugs of the ingot mold, 5 are the bottom or hold-down lugs of the ingot mold to assist in holding it down while the ingot is being 100 withdrawn therefrom, 6 are lifting staples for convenience in handling the molds, 7 is the inner cavity of the ingot mold illustrated in Figure 1, 8 is the mold stool of Figure 1 having a depression 9 of curved form to 105 form the bottom end of the ingot, 10 are lugs or pads on the stool 8 to aid in positioning the ingot mold thereon; 11 is the inner cavity of the ingot mold illustrated in Figure 2, 12 is the lower and more tapered part of the 110 bottom portion of the ingot mold 2, 13 is the mold stool illustrated in Figure 2 provided with an internal projection 14 which is of slightly less size than the bottom of the mold which surrounds it, 15 indicates 115 clay or slurry or other sealing material which may be placed between the edges of the projection 14 and the lower inner portion of the mold 2, and 16 are lugs which aid in positioning the mold 2 on the stool 13. 120 Clay slurry or other sealing material may be placed between the bottoms of the molds 1 and 3 and the stools 8 and 20 to seal the joint or crack to prevent fins. This mold 2 weighs about one and one-half times as much 125 130

as the ingot contained therein. 17 is the inner mold cavity of the mold 3 illustrated in Figure 3, 18 is the lower concave curved inner portion of the mold 3 and 19 is the convex continuation thereof to provide a smaller bottom end on the ingot for the reasons previously mentioned, and 20 is the mold stool for the mold 3 which has a plane top. The ingot mold 3 weighs about four times as much as the ingot formed therein.

21 is the metal casing containing the refractory material of the sink-head top, 22 is the base flange of the casing adapted to be set on the top of the mold, 23 are downwardly projecting lugs on the base of the sink-head casing adapted to center and position it on the top of the mold, 24 are lifting lugs preferably made integral with the sink-head top casing, 25 is the top flange of the casing, and 26 represents dried sand, loam or other refractory non-conducting lining forming the sink-head top for the purposes previously mentioned.

Another feature of particular value is that my thick and heavy ingot molds have so much heat-absorbing and containing capacity on account of their mass that they can be used for casting ingots therein while the molds are at higher temperatures than the ordinary lighter ingot molds, and they thereby do not so suddenly chill the surfaces of the ingot, which sudden chilling produces surface defects in the ingots, which are obviated by the use of my molds.

Although I have shown and described my invention in considerable detail, I do not wish to be limited to the exact and specific details thereof, as shown and described, but

may use such modifications in, substitutions for, or equivalents thereof, as are embraced within the scope of my invention, or as pointed out in the claims.

Having thus described my invention, what I claim and desire to secure by Letters Patent is:—

1. An ingot mold with its large end up, provided with side walls of substantially uniform thickness such that the weight of the mold is from one and one-half to four times the weight of the contained ingot.

2. An ingot mold with its large end up, provided with side walls of substantially uniform thickness such that the weight of the mold is from two to two and one-half times the weight of the contained ingot.

3. An ingot mold with its large end up, provided with side walls the major portions of which are of substantially uniform thickness such that the weight of the mold is from two to two and one-half times the weight of the contained ingot, the lower end of said mold being provided with a straight taper to produce a contracted bottom portion on the ingot.

4. An ingot mold with its large end up, provided with side walls the body portions of which are of substantially uniform thickness such that the weight of the mold is from two to two and one-half times the weight of the contained ingot, the lower end of said mold being provided with a curved taper to produce a contracted bottom portion on the ingot.

In witness whereof I hereunto affix my signature.

LOUIS R. CUSTER.
